UNITED STATES PATENT OFFICE.

ROBERT B. TUFTS, OF KIRKWOOD, GEORGIA.

INSTALLATION OF CONCRETE FOOTINGS FOR PILES AND THE LIKE.

1,396,542.

Specification of Letters Patent.

Patented Nov. 8, 1921.

Application filed April 13, 1920. Serial No. 373,495.

To all whom it may concern:

Be it known that I, ROBERT B. TUFTS, a citizen of the United States, and a resident of Kirkwood, in the county of Dekalb and State of Georgia, have invented certain new and useful Improvements in Installation of Concrete Footings for Piles and the like; and I do hereby declare the following to be a full, clear, and exact description of the invention, such as will enable others skilled in the art to which it appertains to make and use the same.

This invention relates to improvements in the installation of footings for concrete piles and the like,—one object of the invention being to provide a footing or foundation for a pre-formed concrete pile in such manner that the same may be easily and quickly formed and established under the pile after the latter shall have been driven into the soil.

With this and other objects in view, the invention consists in certain novel features and method of procedure as hereinafter set forth and pointed out in the claims.

In the accompanying drawings, Figure 1 is a view illustrating a driven concrete pile, before the footing has been formed; Fig. 2 is a view showing the manner in which a space is provided under the bottom of the pile to permit the subsequent formation of the footing, and Fig. 3 is a view illustrating means employed for and the manner of forming and establishing the footing or foundation for the pile.

1 represents a pre-cast concrete pile having suitable reinforcement 2 and a central longitudinal opening or bore 3 extending from end to end thereof, and in this opening, a metal tube 4 may be located to prevent particles of concrete entering said opening. Before driving the pile, it is provided with a separate driving point or block 5 of concrete or other material and preferably made tapering and having a metal nose 6. This nose is provided with an internally threaded socket 7 to receive the threaded lower end of a rod 8 passing through the pipe or tube 4, said rod having a headed upper end 9 and serving to retain

the driving point or block 5 in position against the lower end of the pile while the latter is being driven.

When the pile shall have been driven as shown in Fig. 1, the rod 8 will be unscrewed from the driving point 5 and removed. A plunger 10 will then be passed freely through the tube 4 and caused to engage the driving point. The plunger 10 will now be subjected to the action of a driver, such as illustrated diagrammatically at 11, for the purpose of forcing the driving point 5 downwardly from the lower end of the pipe and thus form a space 12 below the pile. The plunger 10 will then be removed and the upper end of the longitudinal bore of the pile or, when the tube 4 is employed in the pile, the upper end of said tube will be connected by a pipe 13, with the outlet of a hopper 14. This hopper may be supported by suitable legs 15 on a boat or float 16 and it is provided at its top with an inlet opening adapted to be sealed air tight by a cover or door 17. The hopper 14 is connected by a pipe 18 having a valve 19, with a tank 20 of compressed air or other fluid pressure medium, such as steam.

After charging the hopper 14 with concrete or kindred material in semi-liquid form, the cover or door 17 will be tightly closed and then the contents of said hopper will be subjected to fluid pressure from the tank 20, by opening the valve 19 in pipe 18. Such fluid pressure will operate to force the concrete through the pipe 13 and through the tube 4 in the pile to the space 12 under the pile. As the earth into which the pile has been driven is soft, the wall of the space 12 will yield to the pressure of the concrete entering said space and as the pressure to which the semi-liquid concrete is subjected continues, the mass of concrete below and around the lower end of the pile will increase in size until a substantial concrete footing 21 for the lower end of the pile will be established.

A small pipe 22 may be embedded in the concrete of the pile so that its lower end will communicate with the space 12 so as to provide means of escape of air which might

be trapped in said space during the initial stage of establishing the footing and a valve 23 may be provided in this pipe for closing the same so that the development of sufficient fluid pressure on the semi-fluid concrete will not be interfered with.

In some kinds of earth, such as quick sand or other semifluid earth, the walls of the cavity under the pile might cave and the cavity might be filled up by the earth entering the same.

To prevent this cavity or space under the pile in the wake of the point from filling up with earth, I propose to employ a bore 15 in the pile considerably larger than the diameter of the plunger and enough larger to permit of the hole in the pile with the plunger placed therein, to hold enough grouting material to more than fill the space 20 under the pile to be caused by forcing the point farther down.

Then just before the point is to be forced down and either before or after the plunger is placed ready to force the point down, a 25 sufficient quantity of semifluid cement and water mixture will be poured in the bore of the pile so that when the point is forced farther down the fluid cement mixture will run into the space as it is being formed and 30 will thus prevent the sides of the cavity from running into the space being formed. Of course little time should be lost after filling the initial cavity until the entire footing shall be developed, as otherwise the first 35 grout might harden and stop further operations.

Having fully described my invention what I claim as new and desire to secure by Letters Patent, is:—

40 1. The herein described method of establishing a concrete footing for a pile, consisting in forcing a driving member downwardly beyond the lower end of a tubular driven pile and thereby forming a space 45 below the pile, and forcing semi-liquid concrete through said driven pile and into such space under sufficient pressure to enlarge said space and establish a concrete footing for the pile.

50 2. The herein described method of establishing a concrete footing for a pile, consisting in temporarily connecting a separate driving member to a pile having a longitudinal bore, forcing said driving member 55 downwardly beyond the lower end of the pile after the latter shall have been driven, thereby forming a space below the pile, and forcing semi-liquid concrete through the bore of the pile and into said space with 60 sufficient pressure to enlarge said space and establish a concrete footing for the pile.

65 3. The herein described method of establishing a concrete footing for a pile, consisting in driving a concrete pile having a longitudinal passage and a separate driving

member temporarily secured to the lower end of said pile, disconnecting said driving member from the pile, passing a plunger through the passage in the pile, applying force to said plunger to drive the driving member downwardly from the pile, thereby forming a space below the pile, removing said plunger, and then forcing semi-liquid concrete through the passage in the pile and into said space with sufficient pressure to 70 enlarge said space and establish a concrete footing for the pile.

4. The herein described method of establishing a concrete footing for a pile, consisting in driving a tubular concrete pile with 80 a separate driving point at the lower end thereof, discharging semi-fluid cement and grouting into the bore of the pile, forcing the separate driving member downwardly beyond the lower end of the pile, and forcing concrete through the tubular pile and into the space between the lower end of the pile and the separated driving member, whereby an enlarged footing is formed for the pile.

90 5. The combination of a concrete pile having a longitudinal passage, a driving member, means for temporarily securing said driving member to the lower end of the pile, means for forcing said driving member downwardly away from the lower end of the pile after the latter shall have been driven, and means for forcing semi-liquid concrete under pressure through the passage in the pile and into the space between the pile and 100 the separated driving member.

6. The combination of a concrete pile having a longitudinal passage, a separate driving member, a removable rod to pass through the pile and temporarily secure the driving member thereto, a plunger to pass through the passage in the pile after removal of said rod and engage the driving member to force the latter from the pile after the latter shall have been driven, means for connecting a supply of semi-liquid concrete with said passage, in the pile, and means for subjecting said semi-liquid concrete to fluid pressure.

115 7. The combination of a concrete pile having a longitudinal bore, a tube extending through said bore, a separate concrete driving member, removable means for temporarily securing said driving member to the pile, means for forcing the driving member away from the lower end of the pile after the latter shall have been driven and after removal of the temporary securing means to form a space under the pile, a valved pipe embedded in the pile and adapted to communicate at its lower end with said space, and means for forcing concrete under pressure through the tube in the pile and into the space between the pile and said driving member.

8. The combination of a pre-cast concrete end of the pile and the separated driving pile having a longitudinal bore, a separate driving member at the lower end of the pile, removable means insertible through the bore 5 of the pile after the same and the driving member shall have been driven and operable to force the separate driving member downwardly away from the lower end of the pile, and means for forcing concrete through the 10 pile and into the space between the lower

In testimony whereof I have signed this specification in the presence of two subscribing witnesses.
